US00D955079S

(12) United States Design Patent (10) Patent No.: US D955,079 S
(45) Date of Patent: * Jun. 14, 2022

(54) IRONING BOARD STAND

- (71) Applicant: JOSEPH JOSEPH LTD., London (GB)
- (72) Inventor: Antony Joseph, London (GB)
- (73) Assignee: JOSEPH JOSEPH LTD, London (GB)
- () Term: 15 Years
- (21) Appl. No.: 29/763,669
- (22) Filed: Dec. 23, 2020

(30) Foreign Application Priority Data

- Jun. 25, 2020 (EM) 008021760-0001
- (51) LOC (13) Cl. 07-05
- (52) U.S. Cl. D32/66
- (58) Field of Classification Search
- USPC D32/9, 35, 60, 66; D21/526; D6/368, D6/681, 691.6; D8/370
- CPC A47B 39/06; D06F 81/00; D06F 81/003; D06F 81/006; D06F 81/02; D06F 81/04; D06F 81/06; D06F 83/00; Y10S 38/02; Y10S 38/03; Y10T 292/305

See application file for complete search history.

(57) CLAIM

The ornamental design for an ironing board stand, as shown and described.

DESCRIPTION

FIG. 1 is a top perspective view of an ironing board stand in an extended position showing my new design.

FIG. 2 is a bottom perspective view thereof.

FIG. 3 is a side view thereof.

FIG. 4 is another side view thereof.

FIG. 5 is a top view thereof.

FIG. 6 is a back view thereof.

FIG. 7 is a front view thereof.

FIG. 8 is a bottom view thereof.

FIG. 9 is a top perspective view of the ironing board stand in a folded position.

FIG. 10 is a bottom perspective view thereof.

FIG. 11 is a side view thereof.

FIG. 12 is another side view thereof.

FIG. 13 is a top view thereof.

FIG. 14 is a back view thereof.

FIG. 15 is a front view thereof; and,

FIG. 16 is a bottom view thereof.

The broken lines in the drawings illustrate portions of the ironing board stand which form no part of the claimed design.

1 Claim, 16 Drawing Sheets
